FIG. 1

FIG. 2

FIG. 3

UNITED STATES PATENT OFFICE

1,968,425

SHORTENING CUTTER OR WHIP

Charles A. Rowley, Los Angeles, Calif.

Application July 6, 1932, Serial No. 621,049

3 Claims. (Cl. 259—144)

This invention relates to a shortening cutter or whip.

An object of the invention is to provide a novel construction designed to be used to cut shortening into flour, or for analogous purposes, and which may also be used as a type of whip or beater.

More specifically an object of the invention is to provide a construction of this character having a handle to which a plurality of bowed or flexed wire blades are secured, these blades being held in spaced and approximately transverse alignment, the arrangement of the handle and the blades being such as to facilitate use of the device either as shortening cutter or as a whip.

With the foregoing and other objects in view, which will be made manifest in the following detailed description, and specifically pointed out in the appended claims, reference is had to the accompanying drawing for an illustrative embodiment of the invention, wherein:

Fig. 1 is a view in side elevation of the improved device.

Fig. 2 is a view in end elevation of the same. 25 Fig. 3 is a sectional view taken substantially on the line 3—3 upon Figure 1.

Referring to the accompanying drawing, wherein similar reference characters designate similar parts throughout, the improved shortening cutter or whip comprises a vertical handle 10 which may be formed of any suitable material, preferably wood. Associated with the handle there are a plurality of bowed or flexed wire blades 11, these blades being bowed in a circular manner so that they form greater portions of a circle than a semi-circle. They are held in spaced relation and in approximately transverse alignment, as will appear from an inspection of the drawing. The ends of the wire blades are received in and are held by suitable fittings indicated at 12 and 13. These fittings may be of various constructions but in the preferred form of construction each fitting consists of an ear 14, a body portion 15 suitably corrugated as by 45 corrugations 16 in which the ends of the wire blades 11 are disposed. At the sides of the body portion there are bendable side portions 17 and 18 which are folded inwardly over the ends of the wires 11 which are disposed in the corrugations 16. While the manner of securing the ends of the wire blades in the fittings may likewise vary, I prefer to employ the method of construction disclosed in my copending application Serial No. 623,514, filed July 20, 1932, wherein fittings 55 and wires are used which have previously been

coated with tin. When the fittings and the wires are assembled, the assembled fittings and wires are heated to melt the tin coating on the wires and on the fittings so that the tin coatings will fuse together and in this way the tin will act as a sort of solder firmly anchoring the ends of the wires in the fittings between the body portion 15 and the bendable portions 17 and 18. When the wires and fittings are thus assembled the wires are bowed into the position shown and the ears 14 on the fittings are overlapped. Preferably a single fastening element, such as for example a nail 19, is driven through the two ears and into the bottom of the handle 10, thus fastening the two fittings together and to the handle and causing the upper portions or end portions of the wire blades to converge toward the handle.

It will be appreciated that by this construction the device can be used as a shortening cutter for cutting shortening into flour and for analogous purposes and the arrangement of the handle is such as to facilitate the use of the device as a whip for beating eggs, whipping cream and the like.

Various changes may be made in the details of construction without departing from the spirit or scope of the invention as defined by the appended claims.

I claim:

1. A device of the class described comprising a vertical handle, a plurality of bowed wire blades arranged in approximately transverse alignment, flat fittings in which the ends of the blades are secured, said fittings having ears which are overlapped, and a single fastening means securing the ears together and to the underside of the handle.

2. A shortening cutter or whip comprising an upright handle, a plurality of flexed wire blades arranged in substantially transverse alignment, flat fittings into which the ends of the blades extend, said fittings having bent ears thereon, the ears on the fittings being overlapped and positioned against the bottom of the handle, and a fastening means having a head positioned against the bottom ear and extending through the ears into the bottom of the handle for fastening the ears thereon.

CHARLES A. ROWLEY.
